UNITED STATES PATENT OFFICE.

CHARLES W. MEARA AND ROBERT MEARA, OF OGDEN, UTAH.

BUILDING-BLOCK.

SPECIFICATION forming part of Letters Patent No. 790,514, dated May 23, 1905.

Application filed July 16, 1904. Serial No. 216,901.

To all whom it may concern:

Be it known that we, CHARLES W. MEARA and ROBERT MEARA, citizens of the United States, residing at Ogden, in the county of

5 Weber and State of Utah, have invented new and useful Improvements in Building-Blocks, of which the following is a specification.

This invention relates to artificial-stone blocks employed in building; and its objects 10 are to increase the strength of the block, to adapt it for accurate setting in the wall, whether carried in a sling or not, and to provide continuous vertical and horizontal shafts or channels for ventilation or for pipes conveying water, gas, &c.

The accompanying drawings illustrate the invention, its various features being referred to by letters, similar letters denoting corresponding parts in the several views.

20 Figure 1 is a perspective view of one of the blocks. Fig. 2 is a reduced elevation of several blocks laid in a wall, one of the blocks being in longitudinal vertical section. Fig. 3 is a vertical cross-section of a block, taken 25 near one end; and Fig. 4 is a side view of one of the strengthening-bars.

The letter A designates a building-block. It has end recesses *a a* and edge recesses *a' a'* connected therewith to form a continuous recess around the block. The sides B B are 30 plane and constitute the face of the wall on either side of it. The recesses *a* and *a'* are so located as to secure connecting horizontal and vertical air-spaces throughout the entire

35 wall. While the horizontal spaces would be in alinement, the vertical spaces would be broken continually at each layer of the blocks, and in order to make straight vertical shafts an opening *a²* is formed vertically through 40 each block, this opening being in line with the edge recesses in the blocks above and below it. When laying the blocks in the wall, the sling carrying the block occupies the recesses and is readily removed when the stone is in 45 place.

C is a piece of metal curved into the form of a horseshoe and having at each end a bend *c*. These pieces C are linked together in pairs at their curved parts *c'*, and two pairs of them

are molded in each block, one pair near each 50 end of the block, and are so placed that the open end of each piece will extend on each side of the edge recesses *a*.

Rods or bars D, having bent ends *d*, extend lengthwise through the block between the 55 pieces C, the bent ends of the rods engaging the bent ends of the pieces C.

The different parts of the reinforcement being separable, they are easily adjusted in the mold with the material when the blocks 60 are made and very greatly increase the resisting power of the block against both vertical and lateral pressure and also protect it against fracture from concussion.

Dowel-pins E are adapted to fit into holes *e* 65 in the edge of the block, the pins being so spaced that joints will be broken when the blocks are laid in the wall.

The construction of these blocks enables them to be laid in the wall by unskilled laborers, and the pipes conveying water, gas, &c., can be laid in the shafts provided for them while the wall is going up.

Having described our invention and the manner of using it, what we claim, and desire 75 to secure by Letters Patent, is—

1. A building-block having a continuous recess around its ends and edges, curved metal pieces linked in pairs near each end of the block said recesses in the edges of the block 80 lying between the open ends of said curved pieces, and rods connecting said curved pieces as herein set forth.

2. A building-block having a continuous recess around its ends and edges, dowel-pins 85 in its edges, a vertical opening connecting the edge recesses through the central part of the block, curved metal pieces near each end of the block and rods connecting said curved pieces, substantially as described. 90

In testimony whereof we have signed our names to this specification in the presence of two subscribing witnesses.

CHARLES W. MEARA.
ROBERT MEARA.
